Primary Examiner—Ted Shooman*Assistant Examiner*—C. Tuttle*Attorney, Agent, or Firm*—Burns, Doane, Swecker & Mathis, L.L.P.; William A. Knoeller[57] **CLAIM**

The ornamental design for a main body for an electric fingernail polisher, as shown and described.

DESCRIPTION

FIG. 1 is a left side view of our new design for the main body for an electric fingernail polisher; the opposite side is a mirror image thereof;

FIG. 2 is a top plan view thereof;

FIG. 3 is a bottom view thereof;

FIG. 4 is a front end view thereof;

FIG. 5 is a rear end view thereof;

FIG. 6 is a perspective view thereof;

FIG. 7 is a perspective view on an enlarged scale showing a first optional tool mounted in working position;

FIG. 8 is a perspective view on an enlarged scale showing a second optional tool mounted in working position; and, FIG. 9 is a perspective view on an enlarged scale showing a third optional tool mounted in working position.

The broken line showing of the optional tools is for illustrative purposes only and forms no part of the claimed design.
